UNITED STATES PATENT OFFICE.

DWIGHT S. COLE, OF GRAND RAPIDS, MICHIGAN.

GAS BURNER.

Application filed June 18, 1921. Serial No. 477,001.

To all whom it may concern:

Be it known that I, DWIGHT S. COLE, a citizen of the United States of America, residing at Grand Rapids, in the county of Kent and State of Michigan, have invented certain new and useful Improvements in Gas Burners; and I do hereby declare the following to be a full, clear, and exact description of the invention, such as will enable others skilled in the art to which it appertains to make and use the same.

My invention relates to improved means for burning gases, and more specifically to improved burners forming parts of automatic rapid water heaters, but not necessarily limited in its application thereto.

The objects of my invention are: to provide an improved burner for the gas burned in such automatic rapid water heaters whereby a highly efficient combustion of the gas is instantly attained upon ignition and maintained practically constant thereafter regardless of the period of time the burner is in operation; to prevent heat from accumulating in the upper parts of the burner while the heater is in operation and wasted thereafter; to avoid back-lighting therein without the employment of screens; to prevent objectionable concussions or explosions when the burner is ignited or extinguished; to regulate the air supply to part of the flames as an aid to perfect combustion of the gas without admitting an excessive amount of unheated air to harmfully increase the volume and lower the temperature of the products of combustion passing to the water circulating coils of the heater; to provide a burner of ample capacity for the purpose having its head composed of a single piece or unit adapted to be mounted above and supported entirely by the automatic fuel-controlling means of the heater, and to construct such burner in a simple, durable and inexpensive manner. How I attain these and other objects of my invention will be explained hereinafter and the forms and relations of the parts of the device are shown by the accompanying drawings forming a part of this specification.

A gas burning device constructed in accordance with my invention comprises in combination a ring-type burner head adapted to receive and distribute the gas mixture to suitable burning apertures therein and also to have water circulate in an annular passage therein; means for mount-

ing said head comprising a tubular member adapted for the passage of water therethrough into said annular passages in said head and thence outward from said annular passages; an adjustable air-directing shield over the central portion of said burner head; mixing tubes for gas and air connected with and depending from the bottom of the gas-distributing chamber in said burner head, and nipples mounted axially below and adapted to direct gas upward into said mixing tubes, all as hereinafter shown and described and specifically comprehended in the appended claims.

For an understanding of the invention by which the specified and other ends are attained reference is made to the following description, taken in connection with the accompanying drawings, in which,

Fig. 1 is a vertical section, with parts in elevation, of my improved burner, together with its mounting, means of ignition and supplies of water and gas;

Fig. 2 is another vertical sectional elevation of the device, taken of the plane of line A—B of Fig. 1, perpendicular to the drawing and looking in the direction of the little arrows at the ends of said line;

Fig. 3 is a top view, made at a reduced scale, of the head or main portion of my improved burner, and

Fig. 4 is a bottom view, also made at a reduced scale, of the head or main portion of my improved burner.

Like reference characters refer to like parts in the different figures of the drawings.

Referring to the drawings, Fig. 1 discloses, among other things, my new and improved ignition system for the burners of rapid automatic water heaters and how it serves to ignite the gas issuing from the burning orifices of my improved burner. This ignition system constitutes a separate invention, disclosed in most of its essentials in U. S. Letters Patent No. 951,724, issued to me March 8, 1910, and with an important additional element herewith disclosed is to form the subject matter of another application for U. S. Letters Patent by me at an early date. Figs. 1 and 2 also disclose some elements and features of my new automatic valve mechanism for rapid water heaters, which also forms a separate invention upon which an application for U. S. Letters Patent, Serial No. 469,371, filed May 13,

1921, is now pending. Figs. 1 and 2 further disclose portions of the base of the casing of my improved automatic rapid water heater, but said base forms no integral part 5 of my present invention. My purpose in disclosing these several associated elements of my improved automatic rapid water heater is to show how the assemblage of parts of my new and improved mechanism 10 function together to achieve the desired results.

As disclosed by the drawings, my new and improved gas burner is unique in its class, both in the manner of its being mounted 15 and in that provision is made therein for the circulation of cool water to abstract heat from the metal of the burner and thus prevent any considerable rise of temperature in the upper portions of the head thereof. 20 Moreover, an adjustable shield in the form of a disk is mounted over the central portion of the head of the burner to control and direct the air which rises through openings 25 through the said head into the fire, thus aiding in the combustion of the gas and preventing unheated air from rising and mingling with the products of combustion and harmfully lowering the temperature thereof.

Referring to the drawings: numeral 1 30 designates the base of the casing of my improved automatic rapid water heater, having curved cored passages, 2, therein for conducting gas from its inlet orifice, 3, through the top wall thereof, to nipples, 4, mounted 35 in said top wall adjacent the ends of said passages as shown in Figs. 1 and 2; 5 the outer upwardly-projecting annular rim of base 1 to which the side walls (not shown) of the heater are secured; 6 the central circular aperture through said base, within an 40 annular upwardly-projecting flange 7; 8 the brackets or lugs, formed integrally with flange 7, upon which the main casing, 9 of my improved automatic valve mechanism, hereinbefore referred to, is firmly secured by screws (not shown); 10 the water chambers 45 end of valve casing 9, into which water under service pressure enters through pipe 11; 12 the inner or constantly-supplied gas 50 chamber and 13 the outer or periodically-supplied gas chamber in casing 9; 14 the vertical partition between chambers 12 and 13, having a circular perforation, 15, therethrough; 16 the smooth annular marginal 55 surface surrounding perforation 15 and adapted to form a valve seat; 17 the valve disk (operably mounted in chamber 13) adapted to co-act with valve seat 16 to form 60 a valve to control the flow of gas to the main and igniting burners of the heater as the automatic valve mechanism functions in service; 18 the orifice in bottom of chamber 13 coinciding in form to and positioned over orifice 3 in base 1; 19 the pipe which conducts gas from service

mains to chamber 12; 20 the pipe which receives gas from chamber 12 and supplies it to the constantly-burning small pilot flame or jet 21; 22 the nipple which conducts gas from chamber 13 into mixing tube 23, when the heater is in operation; 24 the tip or jet end of nipple 22; 25 the air inlet orifices in tube 23 adjacent jet 24; 26 the slot through the front wall of tube 23 adjacent flame 21; 27 the flame at slot 26, and 28 the flame at 75 top of tube 23, when the heater is in operation; 29 the water-pistons-element in the cylindrical portion, 30, of water chambers 10, having perforations, 31, through the upper piston thereof; 32 the recess in rear wall 80 of casing 9 which permits the incoming water to freely pass the solid lower piston of pistons-element 29, when the heater is in operation, as clearly shown in Figs. 1 and 2; 33 the lugs at, and 34 the packing inset 85 in the top end of cylinder portion, 30, of casing 9; 35 the tubular mount for the main burner casting; 36 the lugs at bottom of burner mount 35; 37 the screws which pass through perforations in lugs 33 and screw 90 into threaded perforations in lugs 36, thereby securing burner mount 35 to casing 9; 38 the diagonally-transverse partition in tubular burner mount 35; 39 the outlet orifice through the side wall of burner mount 35 95 adjacent partition 38; 40 the inlet orifice through the side wall of burner mount 35 adjacent partition 38 and opposite perforation 39; 41 the top orifice or outlet of tubular burner mount 35; 42 the externally-threaded portion of mount 35; 43 the externally-cylindrical portion of mount 35, from threaded portion 42 to top end, 44, thereof; 45 the main burner casting; 46 the axially-perforated hub or central element of casting 45; 47 the lower internally-threaded portion of hub 46, adapted to engage threaded portion 42 of mount 35 and thereby secure 100 said burner casting upon said burner mount; 48 the axially and cylindrically bored portion of hub 46, adapted to receive and closely fit the portion 43 of burner mount 35 passing therethrough; 49 the internally-threaded upper end of hub 46 adapted to receive the threaded end of pipe 50 therein; 51 the top 105 end of rise-pipe 50, provided with a fitting, 51^a, adapted to readily connect the pipe coils of the heater therewith; 52 the externally-threaded portion of the upwardly-projecting end of hub 46; 53 the internally-threaded ring adapted to engage with and screw upon portion 52 of hub 46; 54 the air-directing shield secured to ring 53 by rivets, 55, passing through perforations in said ring and said shield, as clearly shown in Figs. 1 and 2; 56 the upwardly-turned circumferential margin of shield 54; 57 the hollow arm of burner casting 45, adapted to conduct water from bore 48 in hub 46 to the semi-annular passages, 58, formed in casting 45 115 120 125

for the circulation of water therein each way from the inlet thereto around to the outlet therefrom and thence into the other hollow arm, 59, of the burner casting, which arm 5 conducts the water inward to bore 48; 60 the annular gas-distributing chamber of the burner; 61 the radial slots forming the orifices through which the gas escapes to be burned; 62 the flames formed by the burning 10 gas (two flames being shown in radial profile) as it issues from slots 61; 63 the orifices through the bottom wall of chamber 60, by which the gas enters said chamber; 64 the mixing tubes suspended below orifices 15 63; 65 the flanges at tops of mixing tubes 64, whereby said tubes are securely joined to the main burner casting by screws, 66, passing through perforations in said flanges and thence screwing into corresponding threaded 20 perforations in the bottom wall of said chamber 60, and 67 the apertures through the central portion of said burner head permitting the passage of air therethrough to the interior portion of the flames issuing from 25 slotted orifices, 61, in said burner head.

As heretofore constructed automatic rapid water heaters have generally been equipped with a multiplicity or battery of Bunsen-type burners, each of comparatively small 30 unit capacity. Such burners have comparatively large gas outlets or burning orifices and are equipped with screens adjacent their outlets to prevent the flames at their tops from passing down through their mixing 35 tubes and igniting the gas as it issues from their supply nipples. This action is commonly called "back-lighting" and is a difficult matter to overcome without employing means which produce harmful effects upon 40 the combustion of the gas after such burners have been in service for some time. Particles of dust, floating in the air forced into the mixing tubes by the jets of gas, lodge on and clog the orifices of the screens 45 employed in such burners and thus cause such burners to lose their original efficiency soon after they are put in service, and periodic cleaning or changing of their screens is necessary to continue such burners in service. 50 Moreover, burners having comparatively large jet orifices generally produce considerable concussion upon their ignition or extinguishment, and this is quite a seriously objectionable feature in a water heater 55 installed in private homes, or in many other places. Another considerable defect in the designated burners consists in the fact that the heads of such burners quickly become very hot in service and thus pre-heat and expand the incoming gaseous mixture 60 whereby the capacity of the burners is very noticeably reduced after a brief period of operation. The heat so temporarily stored in the heads of such burners is liberated and 65 harmfully wasted after the fire is extin-

guished and the water has ceased to flow in the heater coils, as such liberated heat is largely absorbed by the standing water in the heater coils, raises the temperature thereof considerably, and thus aids materially in 70 the deposition of lime or other sedimentary material on the inner wall of the heater coils. The above-enumerated defects in the designated and commonly employed types of burners are well known to gas-combus- 75 tion experts.

My improved burner overcomes all of the enumerated defects very effectively by the simple means illustrated by the accompanying drawings and described in this specification, thereby making a distinct advance in 80 the art of gas-combustion as applied to automatic rapid water heaters,

It has long been known that, under ordinary conditions of service, a gas flame will 85 not back-light through an adequately narrow slot forming a burner orifice—the permissible width of the slot increasing as the thickness of the metal in which the slot is made increases. Because they ignite and go 90 out with very little or no concussion, do not back-light, produce good combustion, and are not unduly expensive to construct, the slotted-head burner is a type much to be desired in automatic rapid water heaters. 95 However, this type of burner has not heretofore proven satisfactory, as installed in such heaters, principally because their slotted burning orifices constantly grew narrower from metallic growth, due to being 100 repeatedly heated and cooled through a considerable range of temperature, and they also become clogged with rust, due to the action of the highly corrosive acidulated condensation which frequently drips upon 105 them from the superimposed copper coils in which the water circulates while being heated. In my improved burner the possibility of metallic growth affecting the slots has been eliminated by the water-cooling 110 provided therein which prevents any harmful range of temperatures in the metal in which the slots are located. I have also eliminated any serious corrosion in the slots of my new burner by so arranging the form 115 of the heating coils thereover that no condensation formed on said coils can fall upon said burner slots.

In transferring heat to water in any metallic vessel the highest efficiency results when a maximum difference in temperature exists between the products of combustion and the water. To obtain the maximum temperature of the products of combustion no more air should be admitted into the combustion chamber than is essential for the perfect combustion of the gases, and that amount of air must be properly directed into the jets of flame close to the point where they issue from the burner orifices. To satisfy 120 125 130

the foregoing well-established conditions for high efficiency in my improved water heater I have equipped the burner itself with an adjustable air-deflector and shield, 54, for controlling the air admittted centrally through apertures, 67, in the burner head, and made provision in parts of the heater casing construction (not shown) adjacent to the burner head for preventing an excess of air admission to the combustion chamber externally of said burner head.

Figs. 1 and 2 show that the gas supply for the main burner enters chamber 12 through pipe 19, passes thence through valve 15 into chamber 13, thence through coinciding orifices 18 and 3 into passages 2 leading to nipples 4, from which it discharges upward into mixing tubes 64 (where it is properly mixed with air) and orifices 63 into distributing chamber 60, from which it issues through slots 61 to be burned. A plan view of the arrangement of passages 57, 58 and 59 is shown by dotted lines in Fig. 4. Figs. 1 and 2 also show that the water supply to the heater enters chambers 10 through pipe 11, passes through recess 32 and holes 31 (in the upper piston of pistons-element 29) into and through burner mount 35, orifice 39 and hollow arm 57, at the outlet end of which the stream divides into two streams which pass through semi-annular passages, 58, to the opposite side of the burner head where said two streams unite and pass inward through hollow arm 59, orifices 40 and 41, and thence upward through rise-pipe 50 to the coils of tubing in the upper portion of the heater casing. Fig. 1 discloses how the constantly-burning small pilot jet or flame 21 is supplied with gas, through pipe 20, from the constantly supplied chamber 12, and how the burner-igniting flame 27 at the top of tube 23 is ignited by pilot flame 21 through slot 26 when gas is admitted to chamber 13 by the opening of the valve between chambers 12 and 13 when the heater is in operation. Radially profile elevations of two of the flames, 62, of the main burner are shown in Fig. 1, and the radially-cut slotted burning orifices, 61, in the outer wall of the burner casing are indicated, adjacent the outer margin thereof, in the top plan view shown by Fig. 3. The top and bottom plan views of the burner head, shown in Figs. 3 and 4, respectively, disclose the arrangement of hollow arms 57 and 59 with respect to central hub portion 46 and the outer or ring portion of burner casting 45, and these views also disclose the apertures, 67, provided for the passage of air through the burner head. As shown in Figs. 1 and 2, air-directing shield 54 is made of a thin disk of suitable metal secured to ring 53 by rivets, 55, and, as ring 53 screws upon portion 52 of hub 46, it is evident that said air-directing shield can

easily be adjusted, by simply rotating same with respect to casting 45, to control the amount of air admitted to the inner portions of flames 62 and to direct such admitted air properly into said flames. It is to be noted that flames 62 do not impinge upon the outer margin, 56, of disk 54, but are kept from so doing by the rising current of air deflected outward by said disk, and that the cool air rising against the whole lower surface of disk 54 effectively prevents said disk from becoming harmfully heated when the heater is in operation.

As heat flows readily in gray iron castings, and as the entire burner head, 45, is one integral casting of that material, the cool water flowing through its passages effectively prevents any harmful heating of any portion of said burner head, regardless of the length of time the heater is in continuous operation. Moreover, the currents of air which rise through mixing tubes 64 and apertures 67 suffice to keep the burner dry on its exposed surfaces, and no harmful corrosion occurs on said surfaces in practice.

It is to be observed that in water heaters embodying my improved burners the heat first begins to be applied to the water within the burner itself, and, in that regard, my improved burner differs from all others known to me in the automatic rapid water heater field.

From the foregoing disclosures of my invention, and of the enumerated deficiencies of the types of burners heretofore commonly employed in automatic rapid water heaters, it appears that I have produced a new burner of such decided merits as to constitute a decided advance in the art of burning gas in such heaters. The disclosures made show that the several objects of my invention have been achieved by simple, practical and inexpensive means. By making the burning orifices in the form of slots arranged radially, and on the burner profile shown, air to support the complete combustion of the gas is readily drawn in between the thin flames and a highly efficient combustion of the gas is instantly attained upon igniting the burner, while the water-cooling employed in the burner maintains such high efficiency of combustion constantly, regardless of the length of time the heater is in continuous operation. The water-cooling of the main burner prevents harmful and wasteful accumulations of heat in its head. Back-lighting is prevented without the use of screens or any additional parts therefor. Objectionable concussions, when the burner ignites and when it is being extinguished, are prevented by the slots employed for burning orifices. The air supplied to the central portion of the combustion chamber of the heater (above the burner) is effectively regulated by the adjustable air-regu-

lating shield employed, and this aids materially in the efficiency of the heater. The arrangement of the burning orifices on the sloping outer surface of the burner ring produces a burner of large flame capacity in one head of comparatively small diameter and bulk. Said burner head is simply mounted in such a manner as to provide space thereunder for the installation of the automatic valve mechanism controlling the admission of gas to the main and igniting burners of the heater. The entire burner is of a simple and durable construction, and easy and inexpensive to manufacture and install.

15. A burner of substantially the same details of construction as that illustrated by the accompanying drawings and described in this specification has been in constant service in my new automatic water heater for a sufficient period of time to prove its merits beyond any doubt, and I, therefore, claim to have proof of the merits of said burner as they have been set forth.

I consider myself entitled to all forms of burner construction comprehended within the scope of the appended claims defining my invention, viz:

I claim:

1. A burner of substantially circular form adapted to be positioned horizontally and provided with an outer fuel chamber having vertical slots in its outer wall in spaced apart relation to each other, and a circular inner water circulation passage within the outer fuel chamber through which water passes continuously during the operation of the burner.

2. A burner of substantially circular form having an outer annular fuel chamber provided with slots in its outer wall for the escape of fuel for burning, and an inner annular water circulation passage through which water passes continuously during the operation of the burner.

3. A burner formed as an integral casting of substantially circular form and provided with an inner annular water circulation passage and an outer annular fuel chamber, said outer chamber having inlet openings in its bottom wall for the entrance of mixed air and gaseous fuel and with a series of spaced apart slots in its outer wall for the escape thereof for burning, substantially as described.

4. A burner for gaseous fuel comprising an outer annular gaseous fuel and air chamber provided with exit means for the mixed fuel and air therefrom for burning, and an inner annular water circulation passage immediately inside of the fuel and air chamber, said water circulation passage being located around vertical openings through the burner, substantially as described.

5. A burner for gaseous fuel comprising a substantially circular body having two an-

nular chambers located one within the other and having a common wall dividing one from the other, the outer wall of the outer chamber being vertically slotted at spaced apart intervals, a central vertical hub having a lower inlet and an upper outlet, two hollow arms leading from the hub to the inner chamber, and a partition located within the hub separating the passages through the arms from each other whereby water carried into the inlet end of the hub passes through the inner chamber and out at the outlet end of the hub.

6. A horizontally located burner provided with an annular water circulation passage therethrough, a vertical hub to the burner having inlet and outlet ends connected with said passage, and means dividing the hub to thereby separate the inlet and outlet ends thereof, substantially as described.

7. A burner comprising a vertical hollow hub-like member having inlet and outlet pipes connected to its lower and upper ends respectively, hollow arms extending from opposite sides of said hub-like member and having the passages therethrough communicating with the vertical hollow through said hub-like member, an annular member carried by said hollow arms and having two annular chambers therein—the inner one of said chambers connecting with the passages in said hollow arms and the outer one having a plurality of vertical spaced-apart slots formed in its outer wall, and a diagonal partition extending across the vertical bore in said hub-like member to separate the inlet and outlet ends thereof.

8. In combination, a burner comprising an annular member, a central vertical hub to which the member is connected, there being vertical openings through the burner between the annular member and hub, and a plate located horizontally over the burner and attached to the upper end of the hub, said plate having an upturned outer margin extending beyond the vertical openings through the burner, substantially as described.

9. In combination, a burner comprising an annular member, a central vertical hub around which the annular member is horizontally located and to which it is connected, said member having an annular chamber therein for mixed air and gaseous fuel and in the outer wall of which a plurality of spaced apart vertical slots are cut, said burner being provided with central vertical passages therethrough between the hub and annular member, and a plate adjustably mounted for vertical adjustment on the upper end of the hub, said plate being horizontally positioned and extending at its outer portions over a portion of the annular member, substantially as described.

- 6
10. In combination with a vertical inlet water pipe, a burner horizontally located at and around the upper end of said pipe, an annular water passage in said burner with one end of which the pipe connects, a riser pipe connected with the opposite end of said passage, said burner also including an annular chamber around the water passage formed with openings in its bottom wall and with a consecutive series of vertical slots spaced apart in its outer wall, mixing tubes connected to and depending from the burner, one at each of said openings in the bottom wall of the annular chamber, and gaseous fuel nipples located at the lower ends of the mixing tubes, substantially as described.
11. A burner of circular formation having an annular fuel chamber, the outer wall of which is provided with slots for escape 20 of the fuel for burning, and also having an annular passage inside of the fuel chamber for the circulation of water, the inner wall of the fuel chamber comprising portions of the ends of said annular passage for carrying water to and away from said water passage through the burner.

In testimony whereof I affix my signature.

DWIGHT S. COLE.
